DEVICE FOR IMPARTING RECIPROCATORY
AND OSCILLATORY MOVEMENT TO BABY
CARRIAGESFrederick Daniel Fraunfelder, Elva L. Burner,
and Otto E. Bugs, Janesville, Wis.

Application October 17, 1949, Serial No. 121,771

3 Claims. (Cl. 180—1)

1

This invention comprises novel and useful improvements in a baby tender and more specifically pertains to an apparatus for automatically imparting rolling and rocking agitation to a baby carriage for predetermined timed intervals.

The principal purpose of this invention is to provide an automatic mechanism for imparting for predetermined timed intervals a controlled and adjustable rolling reciprocating and oscillatory vibratory movement to a baby carriage to assist in pacifying and soothing infants therein in a safe and secure manner.

A further object of the invention is to provide a device wherein each wheel in a baby carriage may be guided during a reciprocatory movement thereof, and wherein each wheel may be selectively and independently adjustably elevated by the device, and adjustably and independently vertically oscillated by the device during reciprocatory movement of the carriage.

A still further object of the invention is to provide an improved means for imparting a reciprocatory motion to a baby carriage while restraining the same to a rectilinear guided path of travel.

And a final important object of the invention, to be specifically enumerated herein, is to provide an improved means for securing a baby carriage in a readily detachable manner to the device for operation thereby, and to readily adjust the length of the path of travel and consequently the speed of the reciprocatory movement of the carriage under the control of the device.

These, together with various ancillary objects and features of the invention which will later become apparent as the following description proceeds, are attained by the present invention, a preferred embodiment of which has been illustrated by way of example only, in the accompanying drawings, wherein:

Figure 1 is a side elevational view showing the present invention applied in operative relation to a baby carriage for operation of the same;

Figure 2 is a fragmentary view similar to Figure 1, parts being broken away;

Figure 3 is a horizontal sectional view through the baby carriage operating device;

Figure 4 is a vertical longitudinal sectional view through the device, taken substantially from the plane of the section line 4—4 of Figure 3;

Figure 5 is a vertical transverse sectional view taken substantially on the plane of section line 5—5 of Figure 3;

Figure 6 is a fragmentary vertical sectional de-

2

tail view through a portion of the driving mechanism of the invention; and,

Figure 7 is a further elevational view, parts being shown in vertical section, through the fastening means for securing the operating connection of the device with the baby carriage.

Referring now more specifically to the accompanying drawings, wherein like numerals designate similar parts throughout the various views, it will be seen that there is disclosed a device indicated by the numeral 10 and constructed in accordance with the principles of the invention, and which is operatively associated with a baby carriage indicated generally by the numeral 12, 10 and which consists of axles 14 by means of which the baby carriage is supported on the customary wheel 16.

In accordance with the principles of the invention, each of the wheels of the baby carriage is 20 mounted to abut the separate supporting rail. Each of the supporting rails consists of a base member 18 having an inclined upper surface 20, together with an upper rail 22, having a correspondingly inclined lower surface, whereby the upper rail may be placed upon the lower rail with the inclined surfaces in juxtaposed position, and longitudinally moving the upper rail with respect to the lower rail, the vertical elevation of the upper surface of the upper rail may be varied as desired. Any suitable means will be provided for securing the upper and lower rail together in properly adjusted position, it being now understood that each of the wheels of the carriage may be separately vertically moved by adjustment of the complementary rail portions.

As shown in Figure 2, each of the upper rails is provided with upstanding lateral side flanges 24, these flanges constituting guide means for retaining the wheel 16 upon the upper rails for guided rectilinear reciprocation therealong as set forth hereinafter.

Each of the upper rails is preferably provided with one or more longitudinally spaced apertures at the upper surface thereof, for the reception of the shank portion 26 of a button member 28. By this means the button 28 may be adjusted longitudinally of the upper rail 22, and will constitute a protuberance extending above the surface of the same whereby upon reciprocation of the carriage, the wheel of the same will be given a jolt or vertical oscillation during its reciprocation. Obviously, the buttons may be so positioned as to impart such a jolt simultaneously to each of the wheels of the carriage; it is preferred to have these vibratory impacts of the wheels

upon the buttons recur in various spaced relations in order that a rocking as well as a vertical agitation or oscillation may be imparted to the carriage during its reciprocation.

In conjunction with the above described supporting rails, the device further includes means for imparting reciprocatory motion to the carriage while the same is supported on the supporting rails for reciprocation thereupon. This operating means conveniently comprises a housing consisting of a supporting base 30 having upstanding side walls 32, this base being of any suitable shape and character, as desired. The side walls may be detachably secured to the base in order to obtain access to the interior, thereof, the upper ends of the side walls being inturned to provide a top cover 34, this cover being provided with a longitudinally extending slot 36 disposed medially and longitudinally of the casing for a purpose which will be subsequently apparent.

If desired, the housing may be secured in fixed relation to the supporting rails in a desired manner as by mounting the same upon a common supporting base or the like.

Suitably mounted within the housing is a prime mover operating means preferably in the form of an electric motor 38 of any suitable construction, the same being provided with a cooling fan 40, the casing having ventilating louver 42 for permitting the circulation of air therethrough as shown in Figure 5.

The motor is connected with a suitable electric circuit (not shown) in any desired manner, this connection preferably including an electric conducting cable 44, having a connection 46, from which the same may be connected with a conventional outlet plug in an electric circuit. The cable 44 preferably includes a timing switch 48 of any conventional design, this switch being adjusted to complete the electric circuit for various selected periods of time. The construction of such a switch is simple and well known, and forms no part of the present invention other than its use in such an environment, it is not believed necessary to illustrate the details of construction of the same.

A vertical power shaft 50 is suitably journaled in the casing, and is directly connected as by bevelled gears 52 to the armature shaft of the motor whereby the shaft 50 may be continuously rotated during operation of the motor. At its upper end, the shaft 50 has fixedly secured thereto a plate or disc 54 which is adapted for rotating in a horizontal plane. Conveniently, this disc may overlie the motor 38 in the interest of compactness, and as shown in Figures 3 and 6, the disc 54 is provided with a radial slot in its upper surface, this slot being T-shaped in cross section, thus providing a radial surface slot 56, having a laterally enlarged lower portion 58. As shown in Figure 4, a headed crank pin 60 is adjustably secured and received in this slot, this crank pin having a headed portion 62 which is slidably received and retained in the lateral portion 58 of the slot, while the shank portion of the crank pin extends upwardly through the radial slot 56, and has journaled thereon one end of a connecting rod member 64. This connecting rod member is pivotally retained on the crank pin as by a washer 66 and a fastening nut 68, whereby by rotation of the crank disc 54, and the crank pin 60, a reciprocatory and oscillatory motion will be imparted to the crank connecting rod. It is intended to adjust the crank pin rigidly of the slot 56, a suit-

able locking means may be provided for retaining the crank pin in adjusted position.

By means of a pair of suitable supporting brackets 70 and 72, a pair of parallel, vertically spaced guide rods, 74 and 76, are mounted within the casing, and a connecting member in the form of a block 78 is provided with bores for the sliding movement upon the guide rods 74 and 76. This connecting member has an upstanding pin figured thereon, see Figures 4 and 7, the lower end of this pin being secured as by screw threading into the upper end of the body 78. The other extremity of the connecting rod is rotatably received to abut the pin 80 and is conveniently retained thereon as by a pair of collars 82 and 84. It will thus be seen that the fastening member has imparted thereto a straight and rectilinear reciprocating motion from the continuously rotating power shaft 50.

Upon the upper surface, the pin 80 is provided with a V-shaped upwardly opening recess or socket 86 which is adapted to receive the above mentioned axle 14 of the carriage at substantially its mid-point. In order to retain the axle in the supporting socket, a cap or clamping member in the shape of a U-shaped bracket 88 is slidably received on the upper end of the member 80, this member 88, as shown in Figure 1, having vertical slots in its side walls as at 90, in order that the same may straddle the axle 14. By means of a thumb screw 92, the clamping member 88 may be detachably secured to the member 80 to clamp the axle in its socket 86.

From the foregoing, the operation of the rocking mechanism will now be readily understood. A timing switch 48 is set for any desired time interval, such as, for example, as a period from 10 minutes to one hour, whereupon the motor 38 will be energized. Upon rotation of the motor, the crank disc 54 will be rotated, imparting reciprocating oscillation to the connecting rod 64, thus causing reciprocatory rectilinear motion of the fastener 78 upon the guide rods 74 and 76 and to the connection of this fastener with the axle of the carriage causing reciprocatory motion of the same. This reciprocatory motion of the carriage in turn, through the members 28, may be utilized to impart oscillation, or vibration to the carriage during the reciprocation.

During this operation the carriage is firmly connected to the actuating mechanism so that the carriage is handled with safety at all times, while the extent of the speed of reciprocation can be controlled by the stroke of the crank member 50 while the extent of the agitation can be likewise as suggested.

It will thus be seen that there has been provided a compact, sturdy, and yet highly efficient device which can safely roll and rock a baby carriage for an adjustable period of time, and wherein in various types of agitation and rocking movement can be imparted to the carriage, as will be found to be most effective in pacifying, in soothing, or otherwise contributing to the enjoyment of an infant. The device thus provides automatic means which will minimize, if not eliminate, the personal attendance of a baby sitter, with a considerable saving in time.

When the axle 14 is directly attached to the member 80, as in Figures 1 and 7, the buttons 26, 28 are omitted in order to avoid any likelihood of jarring and damaging the rigid operating members 74 and 76. When the buttons are employed, a connecting rod 93 secures the axle 14 to the member 80, as shown in Figure 2, to allow a

swiveling action between the members 80 and 14 to accommodate the vertical displacement occasioned by the buttons 26, 28.

From the foregoing, the construction and operation of the device together with its many advantages, will be quite apparent, and further description is believed to be unnecessary. However, since numerous modifications and equivalents will readily occur to those skilled in this art after a consideration of the foregoing specification and accompanying drawings, it is not desired to limit the invention to the exact construction shown and described, but all suitable modifications and changes may be resorted to which fall within the scope of the appended claims.

Having described the invention, what is claimed as new is:

1. A baby carriage rocker comprising adjustable supporting rails for each wheel of a baby carriage, mechanism for imparting a reciprocatory movement of the baby carriage on its supporting rails, said mechanism comprising a source of power including a rotary shaft, a plate fixed on said shaft, said plate having a radially extending slot therein, a crank pin adjustably secured in said slot, a connecting member secured at one end to said crank pin and having a fastener on its other end, a guide for reciprocatory movement of said fastener, said fastener including a body having a carriage axle receiving recess in the upper portion thereof, a cap detachably secured to said body for embracing an axle, said connecting member being pivoted to said body.

2. A baby carriage rocker comprising adjustable supporting rails for each wheel of a baby carriage, and a mechanism for imparting a horizontal reciprocatory movement to the baby carriage on its supporting rails, each of said supporting rails comprising a vertically adjustable rail having means thereon for imparting a vertical oscillation to the carriage wheel supported

thereon as the carriage is reciprocated, said rail comprising an upper member and a lower member, each being wedge shaped with their inclined surfaces being in juxtaposed position whereby longitudinal movement of one upon the other will vary the vertical elevation of the upper member.

3. A baby carriage rocker comprising adjustable supporting rails for each wheel of a baby carriage, and a mechanism for imparting a horizontal reciprocatory movement to the baby carriage on its supporting rails, each of said supporting rails comprising a vertically adjustable rail having means thereon for imparting a vertical oscillation to the carriage wheel supported thereon as the carriage is reciprocated, said rail comprising an upper member and a lower member, each being wedge shaped with their inclined surfaces being in juxtaposed position whereby longitudinal movement of one upon the other will vary the vertical elevation of the upper member, said oscillating means comprising a projecting button mounted on each upper rail member.
